SHIPPING CONTAINER

Alfred A. Hoffmann, Rochester, N. Y.

Application December 7, 1939, Serial No. 307,999

4 Claims. (CL. 206—41)

This invention relates to shipping containers and has for its principal object to provide a novel form of container in combination with combined means for the locating and fastening of an article within the container and for the locking and sealing of the container on the outside thereof.

A further object of this invention is to provide the combined locating and fastening means for the article within the container and the sealing and locking means for the container in the form of a unitary double purpose label which may provide the necessary shipping data on the outside of the container and any desired legend around the article within the container.

These and other objects and attendant advantages of this invention will become more readily apparent from the detailed description of one embodiment thereof which follows, reference being had to the accompanying drawing in which—

Figure 1 is a top plan view of my novel shipping container before it is folded and sealed for shipping.

Figure 2 is an end view thereof.

Figure 3 is a plan view of the combined article locating and fastening member and container locking and sealing member with an article in the form of a cigar attached thereto for shipment in the container.

Figure 4 is an end view thereof.

Figure 5 is an end view of the container with the article in process of being located and fastened in place in the container prior to being locked and sealed thereinto.

Figure 6 is a top plan view of the container as it appears ready for shipment.

Figure 7 is a cross section of the container taken on the line 7,7 of Figure 6.

As illustrated in the several figures of the drawing the container comprises a double shell 1 with the halves A and B hingedly connected along one side thereof, preferably by having bendable connecting areas 3, 3 integrally provided between the halves of the container. Intermediate the bendable connecting areas the halves of the container are spaced by the elongated opening 4 which, in cooperation with the fastening and locking tape 5, provides for proper location and anchorage of an article within the container as will hereinafter appear.

The locking and fastening tape 5 used in the embodiment of the invention illustrated in the drawings comprises a continuous double label which is suitably gummed on the under side thereof. One end of this label is printed with a suitable legend which may indicate the origin 55

of the article and carry to the recipient suitable congratulations and well wishes from the sender, and the other end of the label is printed with the proper form for the address and postal data for the shipment of the container.

As illustrated in Figures 3 and 4 the first mentioned end of the label is wound around the article, a cigar 6 in this case, with its end portion cemented to the back of the label to form a loop 10 that will firmly hold the article attached to the label. The other end of the label is passed thru the opening 4 to locate the article between the halves of the container and hold it intermediate the ends thereof. By bringing the halves A and B of the shell together, as illustrated in dotted lines in Figure 5, the article is thus automatically positioned and held in place in its proper position within the container.

With the article within the container, the portion of the label 5, which passes thru the opening 4 extends from the container and is wound around the outside thereof to tightly draw the halves A and B together and lock the container by attaching the end portion of the label by means of its gummed surface onto the encircling portion thereof.

As illustrated in the figures the end sections of the halves of the container are surrounded by a narrow flange 7 so as to form shoulders on the opposing edges of the halves which contact each other when the container is closed and prevent the halves of the shell from partially telescoping into each other. The omission of the flange along the edges of the central sections of the halves of the container provides a recess 8 on one side of the closed container and the receding edges of the elongated opening 4 provide a recess 9 on the opposite side of the container when it is closed so that the label 5, when wound around the halves of the container is located within these recesses.

While I have shown and described the container as being made up of thin sheet metal, such as sheet aluminum, sheet steel etc., it is to be understood that the container may be made of other materials such as paper, pressed board or fiber, corrugated board, plastics etc. It is also readily apparent that practically any article or a number of articles may be shipped in a container embodying my invention by simply providing the halves of the container with an enlarged outline of substantially half of the article or articles.

From the foregoing it will be apparent that I have devised a new and useful shipping con-

tainer which embodies the features and advantages enumerated in the statement of the invention and the above description, and while I have, in the present instance, shown and described a preferred embodiment which is practical and highly useful, it is to be understood that this embodiment is susceptible of modification without departing from the spirit and scope of the invention or sacrificing any of its advantages.

I claim:

1. A shipping container comprising a pair of shells adapted to form a hollow receptacle between them with a single opening leading thereinto, and a flexible label movable thru said opening with a portion of one end completely surrounding and fixedly attached to the article to be shipped in the container and the remainder of the label projecting from said opening and adapted to be drawn taut and fastened around the outside of the shells to lock said shells together while holding the article independently and fixedly in place within said shells adjacent said single opening.

2. A shipping container comprising a pair of shells adapted to form a hollow receptacle between them, a bendable connection between a portion of the edges of each of said shells adapted to permit the shells to be folded against each other with an opening in line with said bendable connection, a flexible tape member movable in said opening and adapted to be attached to the article to be shipped in the container with one end portion and adapted to be drawn tightly around the outside of said shells with the other end portion to draw and anchor the article into a predetermined position within the shells and

lock the shells together with the article held fixed in the predetermined position.

3. A shipping container comprising a double shell integrally formed side by side, a bendable section intermediate said double shell adapted to provide for the folding of said double shell to form a hollow receptacle between them, said bendable section having an elongated opening therethru to reduce its resistance to bending, a flexible tape member movable in said opening and adapted to be attached to the article to be shipped in the container with one end thereof and have the remaining portion of the tape member adapted to be drawn tightly around the outside of the folded shells to draw the article into a predetermined position within the shells and lock the folded shells together with the article held fixed in the predetermined position.

4. A shipping container having separable, substantially rigid walls with a slot in one of the walls intermediate the ends thereof, a flexible label carrying a legend at one end and mailing directions at the other end, said label being movable thru said slot for complete encirclement and fixed attachment with its legend carrying end thereof to an article to be shipped within the container, and complete encirclement and fixed attachment to the outside of the separable walls with the mailing direction carrying end thereof so as to provide simultaneous independent support and anchorage of the article with the legend added thereto adjacent said slot within the walls of the container and connection of the separable walls and mailing directions on the outside of the container.

ALFRED A. HOFFMANN.
